UNITED STATES PATENT OFFICE

ROSE LIGHT, OF CANTON, OHIO

TOILET-SEAT COVER

Application filed September 6, 1929. Serial No. 390,740.

The invention relates to covers for toilet seats, and more especially to a protective cover made of paper or the like, and so arranged that it may be easily and readily slipped upon or removed from the toilet seat much the same as an envelope.

The object of the improvement is to provide a cover of this character, formed of a heavy but soft paper or the like, preferably such as is used for paper towels, and which may be produced for a small cost and can be readily placed in position for use upon a toilet seat, or removed therefrom.

Another object of the invention is to provide such a seat cover in the general form of an envelope, comprising top and bottom portions joined at their side edges, and also preferably at their front edges, but unjoined at their rear edges, whereby the protective cover may be easily and quickly slid, from front to rear, upon the ordinary toilet seat, a central opening being formed in the cover of substantially the size and shape of the usual opening in a toilet seat.

A further object is to provide such a cover as above referred to, in flat form so that the same may be placed in quantities in a suitable dispensing receptacle, and easily and conveniently removed therefrom, one at a time, for use.

A still further object is to provide such a cover which is ready for use as soon as slipped in place upon the seat, and requires no tearing or opening of perforations or the like.

Another object is the provision of open corners at the front of the cover to provide a portion which may be easily grasped in the fingers to remove the cover from the seat.

The above and other objects, which will be readily apparent from the following description, may be attained by constructing the improved seat cover in the manner illustrated in the accompanying drawing, in which

Figure 1 is a top plan view of the improved seat cover showing the same in position upon a toilet seat;

Fig. 2, a longitudinal sectional view of the same, taken on the line 2—2, Fig. 1;

Fig. 3, a transverse sectional view on the line 3—3, Fig. 1; and

Fig. 4, a front edge elevation of the improved cover in place upon the seat.

Similar numerals refer to similar parts throughout the drawing.

A toilet seat of any usual and well known design is illustrated conventionally for the purpose of showing the application of the improved seat cover thereto, and is provided with the usual central opening 10, preferably of greater width toward the rear end 11, of the seat, and tapered toward the front end 12 thereof.

The protective cover, to which the invention pertains, is made in the general form of an envelope of soft but stiff paper or the like, such as is generally used for paper towels and the like.

This protective cover comprises generally the top member 13 and the bottom member 14, joined together at their side edges, as at 15, and also preferably at their front edges, as at 16, but unjoined at their rear edges, as shown at 17.

Thus the cover may be easily and readily slipped onto the seat, from front to rear thereof, the open rear end of the cover being first slipped over the front end of the seat and then pushed rearward until it is positioned as shown in the drawing.

This cover may be shaped to generally conform to the size and shape of the toilet seat, as best shown in Fig. 1, and the top member may have the central opening 17' therein, of substantially the same size and shape as the opening 10 in the seat.

The lower or bottom member may be of substantially U-shape, as best shown in Fig. 1, the rear portion thereof being cut away 18, as shown in broken lines at 18, in said figure, in order to permit the cover to be more easily placed upon or removed from the seat.

For the purpose of easily removing the cover from the seat, each front corner thereof may be open, as shown at 20, providing a portion which may be easily grasped by the fingers to pull the cover forward and thus disengage it from the seat.

If desired, a tab 21 may be provided at the

forward end of the cover to permit the same to be easily removed from the seat, or from the container in which the covers may be kept ready for use.

5 From the above it will be obvious that a very simple and inexpensive, protective cover is provided, which has sufficient rigidity to permit it to be easily and quickly slipped into place upon the seat, but which at the same time is sufficiently soft to cause no discomfort or inconvenience, while the cover also fully covers the entire seat, thus effectively protecting the user.

10 I claim:

15 A cover of paper and the like for toilet seats comprising a top member and a bottom member joined at their side edges and unjoined at their rear ends so as to permit the cover to be slipped upon a toilet seat, the front corners of the cover being open to permit the same to be grasped to remove the cover from the toilet seat.

20 In testimony that I claim the above, I have hereunto subscribed my name.

25 ROSE LIGHT.
